UNITED STATES PATENT OFFICE.

SAMUEL P. STEEN, OF PHILADELPHIA, PENNSYLVANIA.

AUTOMOBILE-TOP AND CURTAINS THEREFOR.

1,119,125.

Specification of Letters Patent.

Patented Dec. 1, 1914.

Application filed July 8, 1913. Serial No. 777,862.

To all whom it may concern:

Be it known that I, SAMUEL P. STEEN, a citizen of the United States, and resident of Philadelphia, in the county of Philadelphia, State of Pennsylvania, have invented a new and useful Automobile-Top and Curtains Therefor, of which the following is a specification.

My present invention relates to a novel vehicle top and curtains therefor and consists of a novel top, which is supported in a novel manner, whereby it may be readily raised and lowered with a minimum amount of labor by a single operator.

It further consists of a novel construction of bows and a novel manner of mounting the same.

It further consists of a novel construction and arrangement of curtains and brackets therefor, whereby the curtains may be readily removed when desired.

It further consists of a novel construction of a shield for the curtain, whereby the same is brought into close relationship with respect to the bows.

It further consists of other novel features of construction, all as will be hereinafter fully set forth.

For the purpose of illustrating my invention, I have shown in the accompanying drawings, one form thereof which is preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a side elevation of a motor vehicle having in conjunction therewith a top and curtain embodying my invention. Fig. 2 represents a side elevation of a view similar to Fig. 1, but showing the top in full lines in folded position and in dotted lines in partly folded position. Fig. 3 represents a side elevation of an enlarged scale of a portion of Fig. 1. Fig. 4 represents a section on line α — α Fig. 3. Fig. 5 represents a sectional elevation of Fig. 1, showing more clearly the curtains. Fig. 6 represents a transverse section of Fig. 5. Fig. 7 represents, on an enlarged scale, a perspective view of a shield which may be

employed, if desired. Fig. 8 represents, on an enlarged scale, a perspective view of a portion of a bracket and curtain, certain parts having been removed for clearness of illustration. Fig. 9 represents a perspective view of a hook which may be employed, if desired.

Similar numerals of reference indicate corresponding parts in the figures.

Referring to the drawings,—my invention is designed to be employed in conjunction with any desired type of motor or other vehicle, but for purposes of illustration, I have preferred to illustrate the same as used with an automobile body. The top is provided with rear bows 1, rear brace bows 2, front brace bows 3 and front bows 4. The front bows 4 comprise an outer sleeve 5, into which the extension rod 6 extends, said rod being provided with means for locking the same with respect to the sleeve 5, and in the present instance, I have preferred to show the same as being accomplished by means of a cotter pin 7, which passes through the aperture 8 in the sleeve and the aperture 9 in the rod. The rods 6 are mounted on the pins 10 of brackets 11 and secured in position thereon by means of fastening devices 12, such as for example, cotter pins. The rear bows 1 are secured in the usual manner to a bracket 13, which is provided with a stud 14, to which the rods 6 are secured by means of cotter pins or other fastening devices 15 when the top is folded. The front brace bows 3 which are secured to the stud 16 of the front bows 4, when the top is open, are disconnected when the top is closed and secured to a stud 17 on a rear bracket 13 by means of a cotter pin or other suitable fastening device, as will be best understood by reference to Fig. 3.

19 designates one or more stays connected with the cover 20 or the front brace bows 3, each stay being provided with a hook 21, as best seen in Fig. 2, which is adapted to interlock with a pin 22 connected in any desired manner to the vehicle body.

Referring now more particularly to Figs. 1 and 5 to 9 inclusive, I have shown in conjunction with the bows, a novel type of curtain, which may be readily removed or swung out of the way when it is desired to fold the top, and which are adapted to overlap each other so as to partially or wholly close the sides of the top, as desired. 23 110

designates a curtain bracket comprising a bar provided, in the present instance, with apertures 24 therein, which are adapted to receive the upwardly extending portions 25 of hooks 26, the portions 25 being apertured to receive a cotter pin or other fastening device 27, it being noted that an extension 27 is formed on the hooks, in order to increase the bearing for the bracket 23. 10 Each bracket 23 is provided at each end, with a plate 28 which is secured thereto in any desired manner, and offset, as at 29, in order to provide a space between such plate and the bracket 23, through which an adjoining curtain may pass, in order that one curtain will lap over the other. 30 designates posts secured to the plates 29 in any desired manner and adapted to have mounted therein the roll of a curtain 31. A catch 32 is provided controlled by a cord 33, whereby the curtain may be released in order to automatically open, since the curtain is preferably of the spring roller type, which is so well known that it is unnecessary 25 to describe in detail the construction and operation thereof. 34 designates a shield, the upper portion of which is preferably connected with the bracket 23 in any desired manner, said shield passing around the curtain 31 and having its lower end deflected inwardly, as at 35, in order to bring the curtain into close proximity to the bows of the top, as will be understood by reference to Fig. 6. In order that one curtain may 30 overlap the other, the shield is slotted, as indicated at 36, in Fig. 8, and as will also be understood by reference to Fig. 5. The curtains are preferably located inwardly of the bows, which latter are provided with buttons 37 passing through apertures of the usual type in the curtain. The lower ends 40 of the curtains are reinforced and are provided with tabs 38. Each curtain is also preferably provided with an outlook window 39, which are protected by the shield 34 when the curtains are not in use. The top bows are provided with a hook 40, as seen in Fig. 6, so that one end of the bracket 23 may be removed from its fastening device 25 and swung around at an angle thereto and secured to its respective hook 40 when it is desired to fold the top of the vehicle. If desired, the bracket may be bodily removed from the fastening devices 55 carried by the bows. The cord 33 passes through an aperture 41 in the shield 34. Assuming that the top is in open position and it is desired to close the same, it is simply necessary to release the hooks 21 of the stay's 19 from their respective pins 22 and remove the cotter pin 7, whereupon the top may be folded back into the position seen in dotted lines in Fig. 2, the rods 6 are then removed from engagement with the studs 10 of the brackets 11 and are mounted on the studs 14 of the brackets 13, as will be understood by reference to Figs. 2 and 3. The front braces 3 are then removed from the studs 16 and secured on the studs 17, as seen in Figs. 2 and 3. When the parts are 70 in closed or folded position, it is simply necessary to secure the front braces 3 to the studs 16 and the rods 6 to the studs 10, whereupon a single operator may readily and easily draw the top forwardly and secure the stays 19 in assembled condition. 75 The purpose of the fastening devices 7 is to prevent relative movement of the top 20 with respect to the vehicle body, such as might otherwise occur due to the lifting 80 power of the wind or other currents of air produced during the travel of the vehicle. Special attention is directed to the fact that the curtains may be opened or closed to any desired extent so as to provide a free 85 circulation of the air. The curtains, if desired, may be bodily removed and packed away within the vehicle body and if desired front and back curtains, constructed in a similar manner, may be employed in conjunction with the top. The shield will serve to prevent any dirt, dust or foreign material being collected on the curtains when the same are rolled up. Attention is also directed to the fact that all of the curtains are 90 preferably adapted to be operated from the inside of the car and owing to the manner in which they overlap with each other the entire interior of the car is rendered water-proof when the curtains are closed. 100 The curtains are preferably located in different horizontal planes and owing to their novel construction the side of one curtain overlaps the side of the other, the shield 34 being slotted to permit such action to 105 take place. It will now be apparent that I have devised a novel and useful construction of an automobile top and curtains therefor, which embodies the features of advantage enumerated as desirable in the statement of the invention and the above description, and while I have, in the present instance, shown and described a preferred embodiment thereof which will give in practice, satisfactory and reliable results, it is to be understood that the same is susceptible of modification in various particulars without departing from the spirit or scope of the invention or sacrificing any of its advantages. 110 115 Having thus described my invention what I claim as new and desire to secure by Letters Patent, is:—

1. A vehicle top, bracket supporting means carried thereby, brackets comprising 125 bars carried by said bracket supporting means and located in different horizontal planes, curtains mounted in said brackets and adapted to overlap each other, and a shield secured to each bracket and inwardly 130

deflected to engage at all times its respective curtain to cause it to travel in close proximity to said bows.

2. A vehicle top, bracket supporting means carried thereby, brackets carried by said bracket supporting means and located at different horizontal planes, curtains mounted in said brackets and adapted to overlap each other, a shield secured to each bracket and inwardly deflected to engage at all times its respective curtain to cause it to travel in close proximity to said bows, and means to retain said curtains at any desired point of opening.

3. A vehicle top having supporting members, supporting devices carried by said members, brackets comprising bars removably mounted on said devices, curtain supporting means at the ends of said brackets and offset therefrom, and curtains carried by said curtain supporting means, and said curtains being mounted to cause a curtain to pass between the bar and curtain supporting means of the adjacent curtain, whereby said curtains overlap each other.

4. A vehicle top, having supporting members, supporting devices carried by said

members, brackets comprising bars removably mounted on said devices, curtain supporting means at the ends of said brackets and offset therefrom, curtains carried by said curtain supporting means, said curtains being mounted to cause a curtain to pass between the bracket and curtain supporting means of the adjacent curtain whereby said curtains overlap each other, and a shield for each curtain and partly surrounding the same and provided near its ends with a slot through which an adjacent curtain may pass.

5. In a device of the character stated, a bracket comprising a bar having means at the ends thereof to secure the same in position, plates each having one end secured to said bracket and the other end offset therefrom, a curtain carried by said plates, and a shield secured to said bar and partly surrounding said curtain and having its free end at all times in contact with said curtain to serve as a guide therefor.
